UNITED STATES PATENT OFFICE.

EDWARD W. NICHOLS, OF EAST ORANGE, NEW JERSEY, ASSIGNOR TO HIMSELF, AND M. P. SMITH & SONS COMPANY, OF NEW YORK, N. Y., A CORPORATION OF WEST VIRGINIA.

ROTARY SHOVEL.

No. 893,749.

Specification of Letters Patent.

Patented July 21, 1908.

Application filed December 13, 1907. Serial No. 406,272.

To all whom it may concern:

Be it known that I, EDWARD W. NICHOLS, a citizen of the United States, residing at East Orange, in the county of Essex and 5 State of New Jersey, have invented a certain new and useful Improvement in Rotary Shovels, of which the following is a specification.

The invention relates to means for distributing coal or other material, and the object of the invention is to provide a simple and easily operated machine for this purpose, particularly designed for trimming coal in ships' bunkers and like situations in which 15 operating space is limited and rapid work desirable.

The invention consists in certain novel features and details of arrangement and construction by which the above objects are 20 attained, to be hereinafter described.

The accompanying drawings form a part of this specification and show an approved form of the invention.

Figure 1 is a sectional view of a portion of 25 a ship, showing the machine in operation. Fig. 2 is a front elevation of the machine alone, on a larger scale. Fig. 3 is a corresponding vertical section, taken transversely, partly in elevation. The remaining figures 30 are on a still larger scale. Fig. 4 is a plan view of the upper face of one of the shovels. Fig. 5 is a sectional view taken on the line 5—5 in the preceding figure and showing a 35 means for adjusting the shovel at the desired angle. Fig. 6 is a view of the under face of the shovel.

Similar letters of reference indicate the same parts in all the figures.

A A are end frames or supports, of any 40 suitable construction and material, on them near the top is journaled a shaft B shown as driven directly by an electric motor C, but which may be rotated by a belt or otherwise from the same or other type of motor.

On the shaft B is fixed a pinion B' in mesh 45 with a gear-wheel D' secured on a shaft D mounted in bearings in the supports A A below the driving-shaft B. On the driven shaft D near its center is a spider-frame comprising a hub E having four radial arms E' 50 each terminating in a head E'' on which is mounted a shovel F. The spider is shown as a single casting but the hub and arms may be formed separately and bolted together or 55 otherwise joined.

When in operation the machine is supplied with coal, as by the chute M in Fig. 1, which is taken up by the shovels and tossed or thrown in a manner analogous to hand shoveling until the portion of the bunker to which 60 coal is thus delivered is filled; the machine is then successively turned to direct the coal to other portions of the bunker. By employing an electric motor attached to the machine these changes in direction are easily 65 effected by simply shifting the machine.

The shaft D rotates in the direction indicated by the arrow and it is evident that the distance and elevation to which the coal may be thrown will depend upon the speed of revolution and the angular position of the shovels. The high rate of the electric motor is reduced through the pinion and gear-wheel to revolve the shovels at the desired rate which experiments indicate to be about 120 70 turns per minute, and the shovels are adjustably mounted on the heads E'' so that their angles may be varied in conformity to the speed and material and point of delivery.

From the under face of each shovel projects a segmental boss or curved swell F' grooved longitudinally as at f and having a curved slot f' extending transversely therethrough. The adjacent face of the head E'' is hollowed to match to the boss and has a 80 lug E³ which is received in the groove f. The head and boss are secured together by the bolt F² extending through the slot f' from side to side of the boss and passing through the lug E³. The angular position of the 85 shovel relatively to the head may be adjusted by withdrawing the bolt and moving the boss F' to the desired position in the head and again replacing and tightening the bolt. The outer face of the boss and the corresponding recess in the head are preferably 90 scored transversely to form ridges or teeth E⁴ F³ which interlock and securely hold the shovel against changes in position under the strains to which it is subjected.

The form of the shovel is approximately that of the hand-scoop usually employed in coal trimming but preferably narrower at the front; this construction with the angular adjustment tends to hold the coal picked up 105 by the shovel, until the centrifugal force is sufficient to overcome its inertia, usually in about one-sixth to one-quarter of a revolution, and deliver it with the required energy.

The motor, pinion and gear-wheel may be 110

inclosed in a casing, not shown, to exclude dust from these parts, and the machine is preferably constructed so that it may be easily taken apart and re-assembled, thus 5 permitting it to be passed in sections through coal ports and other small openings.

I claim:—

1. In a device of the character described, a support, a shaft journaled therein, means for 10 revolving said shaft, a plurality of shovels mounted on said shaft, and means for altering the angle of said shovels.

2. In a device of the character described, a support, a shaft journaled therein, a spider 15 on said shaft, a shovel located at the outer extremity of each arm of said spider, and means for adjusting the angle of said shovel relatively to said arm.

3. In a device of the character described, a support, a shaft journaled therein, a spider 20 on said shaft, a shovel on each of the arms of said spider, a curved boss on each shovel adapted to match to a correspondingly curved recess in said arm, means for holding 25 said shovel to said arm, and means for revolving said spider and shovels.

4. In a device of the character described, a support, a shaft journaled therein, a spider 30 on said shaft, a shovel on each arm of said spider, a boss formed on each of said shovels and provided with teeth adapted to engage similar teeth on the arms of said spider for the purpose of adjusting the angle of said shovel, and means for holding said teeth in 35 engagement.

5. In a device of the character set forth, a support, a shaft journaled therein, a motor

carried by said support and arranged to rotate said shaft, a spider journaled in said support below said shaft, means for transmitting 40 rotary motion from said shaft to said spider, a shovel mounted at the outer extremity of each arm of said spider and provided with means for adjusting the operating angle thereof.

6. In a device of the character described, a revolving spider, shovels carried by the arms thereof, a curved boss on each shovel, having a longitudinally extending groove therein and a slot extending transversely there- 50 through, each of said arms having a curved recess matching said boss, a lug in said recess adapted to be received in said groove, and a bolt extending through said slot and lug.

7. In a device of the character described, a revolving spider, shovels carried by the arms thereof, a curved boss on each shovel, having a longitudinally extending groove therein and a slot extending transversely there- 55 through, each of said arms having a curved recess matching said boss, a lug in said recess adapted to be received in said groove, a bolt 60 extending through said slot and lug, and teeth on the adjacent surfaces of said lug and recess constructed to interlock and hold said 65 shovel relatively to said arm.

In testimony that I claim the invention above set forth I affix my signature, in presence of two witnesses.

EDWARD W. NICHOLS.
